C. D. PLATT.
ELECTRIC SWITCH,
APPLICATION FILED MAY 1, 1919.

1,317,821.

Patented Oct. 7, 1919.

UNITED STATES PATENT OFFICE.

CLARENCE D. PLATT, OF BRIDGEPORT, CONNECTICUT.

ELECTRIC SWITCH.

1,317,821.

Specification of Letters Patent.

Patented Oct. 7, 1919.

Application filed May 1, 1919. Serial No. 294,043.

To all whom it may concern:

Be it known that I, CLARENCE D. PLATT, a citizen of the United States of America, residing at Bridgeport, Connecticut, have invented a new and useful Electric Switch, of which the following is a specification.

The objects of my present invention are primarily to provide a simple and compact form of switch which will have a high current carrying capacity.

Further objects are to provide such a switch, which will be relatively inexpensive, which can be easily assembled and which will be of rugged nature and not likely to get out of order.

Briefly, the invention resides in the combination with a movable switch element made up of a cross bar carrying flexible bridging contacts having in-turned contact-making end portions for engagement with relatively stationary contacts and operating mechanism consisting of an oscillating shaft carrying a lug having a lost motion connection with an actuator loosely engaged on the shaft and having an operative engagement with the cross bar.

Another feature of the invention is the provision of guide pins which are loosely mounted on the switch base so as to permit of the flexible contacts having a slight sliding movement over the fixed contacts.

Additional features of the invention will appear as the specification proceeds.

In the accompanying drawing I have illustrated the invention embodied in one of its simple commercial forms but would have it understood that variations may be made from this disclosure without departure from the true spirit and scope of the invention as defined in the appended claims.

In said drawings:

Figure 1, is a plan view of the invention as embodied in a switch of the "inclosed" type, the switch box in this case being shown open and the cover partly broken away. In this view also the switch operating handle is shown broken away for a portion of its length.

Fig. 2, is a sectional view of the switch taken substantially on the plane of the line 2—2 of Fig. 1, the parts being in the open circuit position.

Fig. 3, is a similar view showing the parts in the circuit closed condition.

Fig. 4, is another sectional view illustrating the parts at the commencement of the

switch opening movement and illustrating in dotted lines the sliding action of the movable contacts in the course of such preliminary movement.

60

7 designates the switch base made of suitable insulating material and supporting on its face the two pairs of spaced relatively stationary contacts 8 and 9. These spaced contacts are adapted to be bridged by the movable contact members 10 consisting each of a single strip of spring metal having the in-turned or doubled-under end contact portions 11 adapted to bear upon the stationary contacts and connected with the main body 70 or back of the strip by the rounded loop portions 12.

These in-turned contact-making ends of the strip when free of the stationary contacts, as in Fig. 2, stand at an angle to the back of the strip and at an acute angle to the face of the relatively stationary contacts so that in engaging the stationary contacts they will first touch at the extreme ends thereof at the points indicated at 13 and will then 80 flatten out into firm flat engagement with the stationary contacts, as indicated in Fig. 3. These arched ends are usually made of spring bronze and of a sufficiently heavy gage of metal to properly carry the current. 85

14 designates the cross bar which serves as a carrier for the spring contacts, said switch bar being constructed in the present disclosure of insulating material and having the contact strips secured to the end portions thereof by screws 15 passed up through the underside of the strips and into the bar. 90

The movable switch element described is guided for reciprocating movements toward and away from the base on guide pins 16 95 over which the bar slidingly fits and these guide pins are loosely engaged in the openings 17 provided therefor in the base.

18 designates the operating shaft journaled above the cross bar and supported in this 100 instance in the opposite side walls of the switch inclosing box or housing 19, said shaft having an angularly extending handle 20 at the outside of the box by which the switch is operated.

105 The operating connections from the shaft to the movable cross bar consist, in the present disclosure, of a yoke-shaped member having side arms 21, 22, loosely pivoted on the shaft and connected in spaced relation 110 by a thrust bar 23, and a lug member 24 fastened upon the shaft between the side

arms of the yoke by a pin 25 and operating between two spaced lugs 26 and 27 carried by the side arm 21.

The thrust bar 23 at the lower end of the 5 yoke engages a wear plate 28 on the cross bar and which is shown secured to said bar by a screw 29.

The movable switch element is thrust outward to the open circuit position by a relatively powerful spring 30 having a seat at 31 in the underside of the cross bar.

In Figs. 1 and 2 the switch is shown in the open circuit position. When it is desired to close the switch, the handle 20 is rocked 15 downwardly. This causes the lug or small lever 24, which is fast on the shaft, to engage the rearward stop 27 on the yoke, whereupon the yoke, acting against the bearing plate, forces the switch bar downward, 20 carrying the flexible arched contacts into firm engagement with the relatively stationary contacts. This final condition is illustrated in Fig. 3. The parts are preferably so proportioned that in this final position 25 the backs of the spring contacts will be buckled or arched inwardly, slightly, to increase the tension of the spring contacts against the stationary contacts, thus producing a firm, intimate engagement of the 30 current carrying parts. When the switch is to be opened the switch handle is thrown upwardly to bring the lever 24 into engagement with the forward stop 26 of the yoke, as indicated in Fig. 4, a positive connection 35 being thereby afforded between the relatively fast and loose elements, causing the yoke to be swung downwardly and finally permitting the spring to thrust the movable contact outward with a quick "snap," this snap 40 movement being permitted by reason of the lost motion between the parts, as will be clear from a comparison of Fig. 4, with Fig. 2, the latter indicating the final open position of the switch.

At the commencement of the switch opening movement the friction between the yoke and the bearing plate affords a temporary connection with the switch movable element which causes the movable switch element to 50 first slide downwardly over the relatively stationary contacts in the manner indicated in dotted lines in Fig. 4. This sliding movement of the engaged contacts polishes and cleans the engaging surfaces, thereby insuring clean engaging faces and good electrical contact.

The switch, it will be seen, is quite simple but the structure and operation is such that it is capable of carrying a heavy current, the 60 switch opens with a quick snap insuring a quick, positive break of the circuit and on the closing of the switch a firm and positive engagement of the current carrying parts is effected. As shown in Figs. 2, 3 and 4 the 65 outstanding portions of the spring bridging

contacts are entirely free to yield in both directions and consequently these contacts can flex and adjust themselves accurately to fit the stationary contacts. This accurate fitting of the relatively movable and stationary contacts is further facilitated by the slight 70 sliding adjustment provided for by the relatively loose guide pins. The parts of the switch furthermore are few in number and relatively simple and are such that they can 75 be easily assembled into the complete switch.

I claim:

1. In a switch of the character described, the combination of relatively stationary contacts, a movable switch member for engagement therewith, a switch operating shaft, an actuator for the movable switch member loosely pivoted on said shaft, a lug fast to the shaft having a lost motion engagement with the actuator, and a spring acting on 80 the movable switch element in opposition to the actuator.

2. In a switch of the character described, the combination of relatively stationary contacts, a movable switch member for engagement therewith, a switch operating shaft, a yoke having spaced side arms pivotally engaged on the shaft, said yoke being connected with the movable switch element for operating the same, a lug secured to the shaft 90 between the arms of the yoke, said yoke having spaced stops for engagement by said lug, and a spring for moving the switch member.

3. The combination with a switch mechanism including a movable switch element, of an operating shaft therefor and connections between said operating shaft and movable switch element comprising levers mounted on the shaft, one of said levers being secured fast to the shaft and the other being loosely pivoted thereon, and said levers having a lost motion engagement with each other and one of the levers making engagement with the movable switch element. 100

4. In a switch of the character described, the combination of two pairs of spaced relatively stationary contacts, a movable switch element comprising a cross bar and two bridging contacts carried thereby for engagement with the spaced pairs of stationary contacts, an operating shaft journaled above the cross bar, switch actuating levers on said shaft, one of said levers being secured fast to the shaft and the other lever 110 being loosely pivoted thereon, said levers having a lost motion engagement with each other and one of the levers adapted to engage the cross bar for shifting the same in a switch-closing direction and a spring exerting tension on the cross bar in a switch-opening direction. 115

5. In a switch of the character described, the combination of two pairs of spaced relatively stationary contacts, contacts for bridg- 120

ing the pairs of stationary contacts and consisting each of an arch of spring metal having in-turned ends adapted to be forced into flat engagement with the stationary contacts, a cross bar connecting said arched spring contacts, guide pins on which the cross bar is slidingly engaged and means for shifting the cross bar to carry the in-turned ends of the arched spring contacts 5 into and out of engagement with the respective stationary contacts.

6. In a switch of the character described, a switch base, pairs of spaced contacts mounted on said base, guide pins up-standing 15 from the base, a cross bar slidingly engaged on said guide pins, contacts carried by said cross bar for bridging the respective pairs of relatively stationary contacts and consisting each of a strip of spring metal 20 secured intermediate its ends to the cross bar and having in-turned end portions forming spring loops and means for shifting the cross bar to carry said in-turned spring loops into engagement with the relatively stationary 25 contacts.

7. In a switch of the character described, a switch base, pairs of spaced contacts mounted on said base, guide pins up-standing from the base, a cross bar slidingly engaged 30 on said guide pins, contacts carried by said cross bar for bridging the respective pairs of relatively stationary contacts and consisting each of a strip of spring metal secured intermediate its ends to the cross bar 35 and having in-turned end portions forming spring loops and means for shifting the cross bar to carry said in-turned spring loops into engagement with the relatively stationary contacts, said means including a 40 lost motion connection and a spring operat-

ing on the cross bar to take up the lost motion with a quick snap in the opening movement of the switch.

8. In a switch of the character described, a base, up-standing guide pins loosely engaged in said base, a switch bar slidingly engaged on said loosely supported guide pins, bridging contacts carried by said switch bar, spaced contacts on the base adapted to be engaged by said bridging contacts and means 45 for shifting the switch bar to carry the bridging contacts into and out of engagement with the stationary contacts, said loose guide pins permitting a limited sliding movement of the bridging contacts on the relatively stationary contacts in the course of said switch opening and closing movements. 50

9. In a switch of the character described, a switch base, spaced contacts arranged in pairs on the switch base, a cross bar guided 55 for reciprocating movement toward and away from said switch base, bridging contacts carried by said cross bar and provided with spring contact portions for engagement with the relatively stationary contacts on 60 the base, a box inclosing the switch mechanism and provided with bearing openings in the opposite side walls thereof above the cross bar, an operating shaft journaled in said bearing opening, a switch actuating 65 member loosely engaged on the operating shaft and having connection with the cross bar for depressing the same toward the switch base, a member fast on the operating shaft and having a lost motion connection 70 with the loose actuating member and a spring for thrusting the cross bar outward 75 toward the operating shaft.

CLARENCE D. PLATT.
